(57) **CLAIM**

The ornamental design for a vehicle door interior, as shown and described.

DESCRIPTION

FIG. 1 is a perspective view of a vehicle door interior showing our new design;

FIG. 2 is a front view thereof; and,

FIG. 3 is a top view thereof.

The broken line showings of the other areas of the door depict environmental subject matter and form no part of the claimed design.

1 Claim, 3 Drawing Sheets

FIG. 1

FIG. 2

FIG. 3
